Primary Examiner—Jeffrey Asch*Attorney, Agent, or Firm*—Richard C. Litman[57] **CLAIM**

The ornamental design for a cellular telephone holder, as shown and described.

DESCRIPTION

FIG. 1 is a perspective view of a cellular telephone holder showing my new design;

FIG. 2 is a front elevational view thereof;

FIG. 3 is a rear elevational view thereof;

FIG. 4 is a top plan view thereof;

FIG. 5 is a left side elevational view with the right side being a mirror image thereof; and,

FIG. 6 is a bottom plan view thereof.

The cellular telephone shown in broken line in FIG. 1, is for illustrative purposes only and forms no part of the claimed design.
